SLOW ELECTROMAGNETIC DEVICE HAVING
THE SAME TEMPERATURE COEFFICIENT
OF RESISTANCE MATERIALS IN ASSIST-
ING WINDINGS

Albert B. Rypinski, Laurelton, Long Island, N. Y.

Original application May 18, 1933, Serial No.
671,767. Divided and this application Jan-
uary 5, 1934; Serial No. 705,466

13 Claims. (Cl. 175—372)

My invention relates broadly to slow electromagnets, reactors and transformers and particularly to structures thereof employing the same temperature coefficient of resistance materials in assisting windings of the devices.

This application is a division of application Serial No. 671,767, filed May 18, 1933, for Slow electromagnets having the same or similar temperature coefficients of resistance materials in differential windings now Patent 2,093,368, granted September 14, 1937, in which I disclose electromagnets, reactors, and transformers employing the same temperature coefficients of resistance in the conductors of the slow coil.

My present invention is directed to a slow electromagnet having windings constituted by materials having the same temperature coefficient of resistance and in which the windings assist one another magnetically.

My present invention is directed to slow electromagnetic devices having windings connected to assist one another magnetically, except as claimed in Patent 2,093,368, supra, and other applications and patents to be cited herein.

All relevant description and claims to a slow transformer, originally in this application, have been incorporated in application Serial No. 8,913, filed March 1, 1935, entitled "Slow transformer", now Patent 2,089,860, granted August 10, 1937.

In my copending application Serial No. 416,877, filed December 27, 1929, now Patent 2,082,121, granted June 1, 1937, and divisional application thereof, Serial No. 699,617, filed November 24, 1933, I disclose and claim slow devices with two paralleled magnetically coupled and opposed windings, utilizing different temperature coefficient materials in each. In my Patent 1,972,112, granted September 4, 1934, based on application Serial No. 608,095, filed April 28, 1932, I disclose and claim a slow reactor with two paralleled, magnetically coupled and opposed windings utilizing the same or similar temperature coefficient materials in each. Other related applications and patents are: application Serial No. 699,616—filed November 24, 1933—for Motor starting systems. Now Patent 2,047,228, dated July 14, 1936. Serial No. 699,618—filed November 24, 1933—for motor control system. Now Patent 2,093,368, dated September 14, 1937. Serial No. 699,619—filed November 24, 1933—for Distribution systems. Now Patent 2,082,122, dated June 1, 1937. Serial No. 699,620—filed November 24, 1933—for Arc welding apparatus. Now Patent 2,009,787, dated July 30, 1935. Serial No. 671,768—filed May 18,

1933—for Coils for slow electromagnets and reactors. Now Patent 1,972,319, dated September 4, 1934. Serial No. 703,313—filed December 20, 1933—for Electromagnetic device. Now Patent 2,068,712, dated January 26, 1937.

One of the objects of my invention is to produce a slow reactor with two paralleled inductively coupled windings connected to assist each other magnetically, employing the same temperature coefficient materials in each.

Another object of my invention is to provide a slow electromagnet employing the same temperature coefficients of resistance materials in assisting windings.

As fully described in the patent applications cited above, the invention may be directed to the production of an electromagnet, a reactor or transformer whose magnetism is caused to change with time and utilized for any purpose to which such a device is suited, such as increasing or decreasing the current or voltage applied to a load to affect the operation of devices connected to the line, or it may be used to alter or hold constant its own power factor, to control a current flowing through it into a load, or for other uses.

Other and further objects of my invention reside in the structures and arrangements more fully set forth in the following specification by reference to the accompanying drawing, in which:

Figure 1 is a schematic diagram showing a pair of paralleled windings connected to assist each other magnetically; Fig. 2 is a sectional view of an electromagnet showing the separate windings comprising my invention; Fig. 3 shows a modification of the electromagnet of Fig. 2 in which the windings are divided into a number of sections; Fig. 4 is a cross sectional view taken through a modified form of electromagnet embodying the principles of my invention; Fig. 5 is a cross sectional view of a further modified form of electromagnet embodying my invention; and Fig. 6 shows another modified form of slow electromagnet.

In all cases two windings are connected in parallel so that any magnetism and magnetic action produced is the resultant of two magnetomotive forces assisting each other. The value of the magnetomotive force of each winding is determined by its ampere turns and in any given coil by the sum of the ampere turns in the two windings. The current in the windings divides in the inverse ratio of the resistances of the windings when supplied with direct current. With magnetism threading the windings on direct current, the currents divide in the inverse ratio of

the resistances, and on alternating current, the currents tend to divide in the inverse ratio of the turns, biased by the resistances of the windings. Since the windings are inductively coupled there is the well understood effect on alternating current of the currents tending to hold themselves in the inverse ratio of the turns. In addition, and contributing to the same result, there is a circulating current generated by one winding and 10 circulating through both, whenever the induced voltages in the windings are unequal. These effects are results of mutual induction between the inductively coupled windings. When, in the claims, mutual induction between windings is 15 mentioned it is to be understood as including all the above effects. If the windings are connected to assist each other and if the total current is constant and the turns are equal, a change in resistance in the windings will not affect the total 20 ampere turns, since what one loses the other gains and their effects are additive. If the current is not held constant but is allowed to vary as the resistance and inductive reactance of the circuit change, and this is usually the case, a pair 25 of assisting windings with the same turns in each will alter their total ampere turns as one winding is heated more than the other due to the increased resistance lowering the line current, and therefore the separate currents in the windings. 30 If the total current is constant and the turns are unequal a change in the relative resistance of two assisting windings will alter the total ampere turns, because, while the amperes lost by one will equal those gained by the other, the ampere turns 35 lost by the one will necessarily be different from those gained by the other, due to the inequality of the turns in the windings. It is thus seen that the magnetism set up by two paralleled windings of unequal turns inductively coupled, and connected to assist each other, will change with variations in the relative resistances of the two windings. 40

It is not essential that the materials be of different temperature coefficients of resistance. 45 If identical materials with a high coefficient are used, and the one is heated more than the other, the resistance of the hotter conductor will rise more than that of the cooler one, alter the current split between them and consequently change the 50 magnetism of the coil. Using the same coefficient materials gives rise to advantages not present where radically different coefficient materials must be employed. For instance, for temperatures not exceeding its oxidation point, or where 55 the heated wire is not exposed to oxidation, copper may be employed in both windings. It is inexpensive, commercially available in many sizes, and easy to handle. Due to its low specific resistance many more turns of copper can be employed 60 for a given resistance than with other conductors, which is an important advantage in electromagnet design. The specific resistance of copper is 10.55 ohms per circ. mil. ft. A copper to copper coil may be more readily constructed than a coil 65 where low coefficient materials, such as one well-known alloy, with specific resistance of 675 ohms per circ. mil. foot, are used.

Where the temperatures are below the melting point of aluminum, aluminum and copper may 70 be used, the aluminum for the hotter coil. Aluminum oxidizes but the oxide once formed is a non-conductor, very tough and elastic, so that it does not scale off. For higher temperatures, copper and nickel may be used, the nickel in the hot coil. Nickel does not oxidize as does copper 75

but is more expensive than aluminum or copper. Other metals may be used, depending on physical and commercial considerations.

All elementary metals except mercury, have a temperature coefficient of approximately .004, as shown in the following table, as given on pages 323, 324 and 325 of the Smithsonian Physical Tables for 1929:

Material	Temp.	Temp. coeff. of res.	Material	Temp.	Temp. coeff. of res.	10
IaIa		°C.			°C.	
Advance			Aluminum	25	.0034	
Constantan	25	.000002	Antimony	20	.0036	15
Calido			Bismuth	20	.004	
Ideal			Cadmium	20	.0038	
Climax	20	.0007	Calcium	20	.0036	
Excello	20	.00016	Copper	20	.00393	
German silver	20	.0004	Gold	20	.0034	
Monel metal	20	.0020	Iron	25	.0052	
Therlo	20	.00001	Lead	20	.0039	20
			Magnesium	20	.0040	
			Mercury	20	.00089	
			Molybde- num	25	.0033	
Manganin	25	Zero	Nickel	25	.0043	
			Palladium	20	.0033	
			Platinum	20	.003	
			Silver	20	.0038	25
			Tantalum	20	.0031	
			Tin	20	.0042	
			Tungsten	18	.0045	
			Zinc	20	.0037	

It will be noted that the alloys are generally of lower coefficient than solid metals. In the claims where I specify materials of equal or substantially equal temperature coefficients, it is to be understood that all elementary metals except mercury are substantially equal to each other, but the solid elementary metals are not substantially equal to the alloys.

Coupled with the use of equal or substantially equal materials is the inherent necessity for producing a higher temperature in one conductor than in the other in order to produce a change in magnetism with time. There are many means of accomplishing this and while I have confined the illustrations to only a few of the forms which the slow electromagnet of my invention may assume, I desire that it be understood that in illustrating my invention in the several forms shown that I do not intend such illustrations to be interpreted in the limiting sense.

The windings may be wound on in alternate layers or arranged as alternate pancakes side by side or in any other suitable manner. A coil may contain more than two windings but in all cases the windings will form the equivalent of two groups in parallel inductively coupled, the total net magnetism produced varying with the heating of the windings.

It is well known that an increase in the inductive reactance of an alternating current coil lowers its power factor, while an increase in its resistance raises its power factor. By constructing a slow electromagnetic device of the type disclosed herein of properly proportioned materials, the increase in inductive reactance and the corresponding increase in resistance may be made to result in a substantially constant power factor. This is of advantage for coils operating in circuits where it is undesirable to lower the power factor when the magnetism of the coil is increased.

Referring to the drawing in detail, Fig. 1 shows the connection of two paralleled windings 1 and 2 arranged to draw current from a pair of lines 8, both supported on the same core 3. Connected as shown, their magnetic effect on the core will

be additive as indicated by the N and S markings, north and south poles, respectively.

Fig. 2 is a sectional view of an electromagnet in which the windings 1 and 2 are placed side by side on the core 3. Armature 3a is movably mounted for magnetic coaction with the pole pieces of the core 3. Heat conducting or insulating material 14 and air space 7 are disposed about the windings to control the heating thereof.

Fig. 3 is a sectional view of a modified form of the electromagnet shown in Fig. 2. The windings 1 and 2 are formed in two sections each and mounted alternately on the core structure 3. Heat conducting or insulating material 14, air spaces 1, and armature 3a are provided as shown in Fig. 2.

The term "leakage reactance" is used to measure the leakage magnetism in a two coil transformer or other magnetic device, that is, the magnetism originating in one coil but not linking with the other. In slow electromagnets or reactors it is important to keep this leakage at a low value.

Fig. 4 shows an arrangement consisting in having the cooler winding 1 of copper adjacent the core 3 and wound and insulated as is common for electromagnets of the usual type. The carrying capacity of the conductor is made sufficient to insure its operation at the accepted temperature rise for electromagnets. The opposing winding 2 designed for higher temperature operation is wound over the other with suitable air spaces or heat insulation or both, or any other means to prevent the heat soaking through into the cool coil and to insure proper heat dissipation from both coils. Assume both coils of the same coefficient material and of the same specific resistance (copper to copper, for instance), and also assume the conductors of the same cross sections and total resistance. On direct current and on alternating current when balanced magnetically, the currents in each of the windings will be equal. The energy expended in each winding will be equal. The heat is measured by the watt loss and the windings would rise to equal temperatures if all other factors were equal.

In the coil described above (Fig. 4), the outer winding may be made to rise to a higher temperature than the inner one by having materials of higher heat conductivity in contact with the inner than with the outer winding. The tubes 20 and 21 and headers 22 and 23 in contact with winding 1, may be of good heat conducting material such as brass or copper, while the tube 24 in contact with winding 2, may be a poor heat conductor such as asbestos. This effect is assisted by the fact that the thermal conductivity of air is lower than that of practically all solid materials. Surrounding one winding with solid material of relatively good conductivity and large radiating surface while the other is mainly in contact with air is a practical means for producing a higher temperature in the winding surrounded by air, providing the cooling effect of air circulation is controlled in the design. Where design conditions require it, the air space 25 may be vented to the outside air or in extreme cases, a forced draft of air may be introduced to keep winding 1 at a low temperature while winding 2 rises to a higher temperature.

I have indicated openings or vents 22a and 23a in headers 22 and 23, respectively, through which a cooling current of air may pass between the rows of turns of the winding 1. The arrows and the legends indicate the passage of the air from

the outside of the coil to winding 1 and out again.

A more pronounced difference results if the resistance of the two windings is changed by altering the turns, putting more on the inner coil and less on the outer coil, as illustrated in Fig. 5, leaving the materials and the wire sizes equal as before.

Another means of producing a higher temperature in one coil than in the other is by altering the ratio of the turns, that is, putting more turns on the inner coil and less on the outer coil, as shown in Fig. 6.

If the total resistance and line current remain the same as before, the inner coil will have less and the outer more current than before. However, their ampere turns will remain the same since the change in turns is balanced by the opposite change in amperes in each winding. The increased current in the outer winding will speed its heating and cause it to rise to a higher temperature than before. As its resistance rises, the current split between the windings will be altered and the net magnetism will change. The temperature rise of the outer coil can be further increased by using a smaller conductor in it than in the inner winding, using the same material as before (copper to copper, for instance). Extra turns will need to be added to the inner coil or turns removed from the outer coil to insure that the light wire gets enough current to insure its heating.

It is to be understood that the various means disclosed for altering the relative heating of the windings are not confined to the design shown in Fig. 4, but apply to any other arrangement within the scope of the invention. I may vary the arrangement from that described above in various ways. In Fig. 6, the hot winding 2 is located adjacent the core and may be with or without an air space 7 between the winding and the core.

It is to be understood that the foregoing descriptions of modifications of my invention apply equally well to electromagnets, reactors and transformers.

While I have described my invention in certain preferred embodiments, I desire that it be understood that modification may be made and no limitations upon my invention are intended other than may be imposed by the scope of the appended claims.

What I claim as new and desire to secure by Letters Patent of the United States is as follows:

1. A slow electromagnetic device comprising a pair of inductively coupled windings connected in parallel one with respect to the other so that the polarity of the magnetism produced by one winding is such as to be additive to the magnetism produced by the other winding, said windings having different numbers of turns and being constituted by materials having the same temperature coefficients of resistance, said materials constituting means, when energized and heated, to substantially and disproportionately alter the resistance of said parallel windings and the sum total of magnetism of said device, said different numbers of turns constituting means, through the transformer action between said inductively coupled windings, to further alter the division of current in said two windings and the magnetism of said device.

2. A slow electromagnetic device for connection in series with a supply line and a load comprising a pair of inductively coupled windings

connected in parallel one with respect to the other so that the polarity of the magnetism produced by one winding is such as to be additive to the magnetism produced by the other winding, said windings having different numbers of turns and being constituted by materials having the same temperature coefficients of resistance, the fewer turn winding having a greater resistance than the other when both said windings are at ambient temperature, said materials constituting means, when heated, to disproportionately alter the resistance of said paralleled windings to a substantial extent and the sum total of magnetism of said device, said different numbers of turns constituting means, through the transformer action between said inductively coupled windings, for causing the currents in said windings to divide in the inverse ratio of their turns, biased by the resistances thereof, to further alter the division of current in said two windings, the higher resistance of said fewer turn windings serving to accelerate the heating thereof when traversed by the current maintained therein partly by said transformer action.

25 3. A slow electromagnetic device for connection to a direct or alternating current supply comprising a pair of inductively coupled windings connected in parallel one with respect to the other so that the polarity of the magnetism produced by one winding is such as to be additive to the magnetism produced by the other winding, said windings having different numbers of turns and being constituted by materials having the same temperature coefficients of resistance, said 35 fewer turn winding having a greater resistance than the other when both windings are at ambient temperature, said device functioning differently as to the production of slow magnetism on direct current than on alternating current, the currents 40 in said paralleled windings dividing in the inverse ratio of the resistances on direct current and in the inverse ratio of the turns of said windings biased by their resistance on alternating current, the substantial disproportionate heating 45 of said windings and substantial disproportionate changes in temperature therein over a time cycle constituting means to produce effective changes in magnetism.

4. A slow electromagnetic device as in claim 3 except that the fewer turn winding has resistance equal to the other when both windings are at ambient temperature.

5. A slow electromagnetic device as in claim 3 except that the fewer turn winding has a lower resistance than the other when both windings are at ambient temperature.

6. An alternating current slow electromagnetic device comprising a pair of inductively coupled windings connected in parallel one with respect to the other to form parallel paths, so that the polarity of the magnetism produced by one winding is such as to be additive to the magnetism produced by the other winding, said parallel paths including only materials having substantially equal temperature coefficients of resistance other than zero, said windings having different numbers of turns, constituting means, through the effects of mutual induction between said windings, when energized, for causing substantial disproportionate changes in the resistance of said paths by substantial disproportionate temperature changes therein, to alter the magnetism of said device.

7. An alternating current slow electromagnetic device comprising a pair of inductively coupled

windings connected in parallel one with respect to the other to form parallel paths, so that the polarity of the magnetism produced by one winding is such as to be additive to the magnetism produced by the other winding, said parallel paths including only materials having substantially equal temperature coefficients of resistance other than zero, said windings having different numbers of turns, the fewer turn winding having a greater resistance than the other when both said windings are at ambient temperature, said different numbers of turns constituting means, through the effects of mutual induction between said windings, for causing the currents in said windings to divide in the inverse ratio of their turns, biased by the resistances thereof, to alter the division of current in said two paths by the disproportionate and substantial changes in resistance thereof over a time cycle, the higher resistance of said fewer turn winding serving to accelerate the heating thereof when traversed by the current maintained therein partly by said mutual induction effect.

8. A slow electromagnetic device for connection to a direct or alternating current supply comprising a pair of inductively coupled windings connected in parallel one with respect to the other to form parallel windings so that the polarity of the magnetism produced by one winding is such as to be additive to the magnetism produced by the other winding, said windings being formed of materials having substantially equal temperature coefficients of resistance and having different numbers of turns, said different numbers of turns constituting means for causing substantial disproportionate changes in resistance with substantial disproportionate temperature changes in said windings, said device functioning differently as to the production of slow magnetism on direct current than on alternating current, the currents in said paralleled windings dividing in the inverse ratio of the resistances on direct current and in the inverse ratio of the turns of said windings biased by their resistances on alternating current.

9. An electromagnetic device comprising a pair of inductively coupled windings having substantially the same temperature coefficients of resistance and connected in parallel one with respect to the other so that the polarity of the magnetism produced by one winding is such as to be additive to the magnetism produced by the other winding, the relative resistances of said windings proportioned to produce disproportionate heating and disproportionate resistance changes therein when energized, heat insulation between windings to permit partial heat diffusion from the hotter to the cooler winding, said heat insulation being proportioned to permit substantial temperature equalization between windings until the total current in said windings exceeds a predetermined critical maximum above which the heat flow through said insulation is insufficient to balance the temperatures, currents greater than said critical maximum serving to produce disproportionate changes in resistance in said windings to alter the magnetism of said device.

10. An electromagnetic device comprising a pair of inductively coupled windings having substantially the same temperature coefficients of resistance and connected in parallel one with respect to the other so that the polarity of the magnetism produced by one winding is such as to be additive to the magnetism produced by the other winding, the relative resistances of said windings being

proportioned to produce disproportionate heating and disproportionate resistance changes therein when energized, heat insulation between windings to permit partial heat diffusion from the hotter to the cooler winding, said heat insulation being proportioned to prevent temperature equalization between windings until a predetermined temperature difference has been maintained for a predetermined time, temperature equalization at the 10 end of said time serving to substantially nullify said disproportionate temperature and resistance change and restore initial magnetic conditions.

11. A constant power factor slow electromagnetic device comprising a pair of inductively coupled windings, said windings being connected in parallel one with respect to the other so that the polarity of the magnetism produced by one winding is such as to be additive to the magnetism produced by the other winding, said windings 15 being formed of materials having substantially the same temperature coefficients of resistance other than zero, means for disproportionately heating said windings, the relative magneto-

motive forces of said windings being proportioned so that the net inductive reactance of said device increases as the resistance increases, to result in a substantially constant power factor with changing magnetism.

12. An electromagnetic device as in claim 8 in which the means for causing substantial disproportionate temperature changes in said windings include differential heat dissipating means associated with the windings whereby with equal 10 amounts of energy liberated in the two windings, said windings will rise disproportionately in temperature.

13. An electromagnetic device as in claim 8 in which the means for causing disproportionate 15 temperature changes in said windings comprises differential heat dissipating means, allowing dissipation from one winding within limits of .5 watt per square inch under maximum load conditions, and dissipation from the other winding within 20 limits of 7 watts per square inch under maximum load conditions.

ALBERT B. RYPINSKI.
